COMBINED SEAM RIPPER AND TWEEZERS

Howard E. Koss, Elmwood Park, Ill., assignor to The Boye Needle Company, Chicago, Ill., a corporation of Illinois

Filed Aug. 29, 1963, Ser. No. 76,383

Term of patent 14 years

(Cl. D22—3)

FIG. 1 is a side elevational view of a combined seam ripper and tweezers, showing my new design;

FIG. 2 is a top plan view thereof, showing the cover for the tweezers in exploded relation;

FIG. 3 is a side elevational view thereof, showing the cover for the seam ripper in exploded relation;

FIG. 4 is a left-hand end view thereof on an enlarged scale with reference to the showing of FIG. 1; and

FIG. 5 is a right-hand end view thereof on an enlarged scale with reference to the showing of FIG. 1.

I claim:

The ornamental design for a combined seam ripper and tweezers, as shown.
